UNITED STATES PATENT OFFICE.

LOUIS FRANÇOIS AUGUSTIN FALKÉ, OF MONTREUIL-SOUS-BOIS, FRANCE.

TOY VEHICLE.

Application filed December 27, 1924. Serial No. 758,446.

To all whom it may concern:

Be it known that I, LOUIS FRANÇOIS AUGUSTIN FALKÉ, residing at 87 Rue Etienne Marcel, Montreuil-sous-Bois, Department of Seine, France, a citizen of the French Republic, have invented certain new and useful Improvements in Toy Vehicles, of which the following is a full, clear, and exact description.

10 The present invention has for its object a toy vehicle of the type composed of two frames each mounted upon a wheeled truck provided with a device opposing their backward movement, these two frames supporting a seat and a foot-rest and being hinged together with stops limiting their downward movement, the vehicle therefore advancing as a result of the successive movements of the trucks towards and away from one 20 another.

The improved toy vehicle is characterized by the following features:—On the one hand the foot-rest is arranged upon the lower part of one of the frames, while the upper part of 25 the other frame is extended beyond the hinged-joint in such a manner as to constitute a lever for direct working by the pull of the arms of the occupant, who at the same time exerts by his feet a thrust upon the lower part of the first frame by means of 30 the foot-rests, these combined forces operating to lift up the frames and therefore to bring the trucks together, the lowering of the frames and the separation of the trucks 35 being then produced by the action of the weight of the occupant's body upon the seat, when the pull of the arms and the pressure of the feet have ceased; secondly, the seat is mounted so as to rock, this device allowing 40 the occupant's body to maintain a normal position whatever be the inclination of the frames; thirdly, one of the wheeled trucks 45 is mounted pivotally in such a manner as to effect the steering, the pivotal member being constituted by a ball-joint device in such a manner that in all its movements this truck can rest constantly and normally upon the ground, whatever be the inclination of the frame mounted upon it. These three characteristic features can exist in combination 50 or separately.

The drawing annexed by way of examples shows three methods of construction of the invention:—

Figures 1 and 2 represent the vehicle in 55 the position of rest, in elevation and in plan respectively.

Figure 3 shows the same in edge view, in the raised position.

Figures 4 and 5 are respectively an elevation 60 and a plan of a modification.

Figure 6 shows on a larger scale a form of ratchet clutch device for opposing the backward movement.

Figures 7 to 12 represent a third form of 65 construction.

Figure 7 shows it in side elevation.

Figure 8 is a front elevation of the forward truck.

Figure 9 shows in elevation the upper part 70 of the toy seen from the rear.

Figure 10 is a plan view of the seat detached.

Figure 11 is a section thereof on the plane A A of Figure 10. 75

Figure 12 is a section of the ball joint pivot for the front truck along the plane B B of Figure 8.

In the example represented in Figures 1 to 3, each truck is constituted by a pair of 80 wheels *a* mounted upon a stationary axle *b*; each wheel is provided with a ratchet clutch device of known type (Figure 6) opposing its backward rotation. The front axle *b* constituting a foot rest carries at its centre a 85 rod *c* which constitutes the steering pivot and which turns in the block *d* on the front frame; upon which are mounted the longitudinal members *e* of this frame; these members connected together by cross-members *f* and *g*, the latter forming a back-rest. Upon the longitudinal members *e* are crossed the longitudinal *h* constituting the rear frame; the longitudinal *h* assembled by the cross-members *i* and *j* are mounted directly upon the rear axle *b*, and terminate at their front extremities in two handles *k*. The front longitudinal members *e* are hinged upon the longitudinal *h* at their crossing points by means of a rod *l* bolted through the four 95 longitudinal members. Upon this rod is mounted pivotally the rockable seat *m* which normally rests at its front edge upon the cross-member *f*. At rest the longitudinal *e* bear on the cross-member *j* while the longitudinal *h* rest upon the extremities of the cross-member *f*. 100

When a child occupies the seat *m* with his

feet resting upon the front axle or steering bar b , he can by bracing himself against this bar, exert a pull with his arms upon the handles k , by leaning first forwards and then straightening himself up; in so doing he raises the four longitudinal members of the frame and thereby the seat m , the front truck scotched by its ratchet device remaining in place while the rear truck moves towards it (Figure 3.) The chains n are then stretched out between the two frames to which they are fixed, limiting in this way the closure of the cross-structure formed by the longitudinal members. If from this raised position the child allows his body to fall again upon the seat m , by ceasing to pull upon the handles k , the crossing point of the longitudinals will fall while these members open out; in this movement, the rear truck being scotched in the backward direction, the front truck now advances thus carrying the whole vehicle with it in its forward movement. The raising and lowering movements succeed one another in this way with continual forward propulsion of the vehicle.

The modification of construction represented in Figures 4 and 5 differs from the first example essentially in that each frame 30 is constituted by a single longitudinal member, the longitudinal e^1 presenting at about its centre a slot o having an opening sufficiently wide to admit therethrough the longitudinal h^1 which pivots upon the bolt l^1 . In 35 this example the rear wheels a are fast upon the rear axle b which revolves in the lower end of the longitudinal h^1 , the ratchet clutch device (Figure 6) acting upon the axle b .

In the third modification (Figures 7 to 40 40), the front frame is constituted by two metal bars e^2 of suitable shape, bolted together upon a wooden spacing member d^1 towards their lower ends.

The rear frame, constituted by a board h^2 45 cut out in the shape of a horse, is fitted between the two bars e^2 . These three members are connected together pivotally by the hinge-bolt l^2 .

The seat m has at its front end a notch m^1 50 into which there fit the withers of the horse h^2 , upon which this seat is fixed pivotally in this position by the hinge-bolt m^2 , of which the head and the nut are sunk in two recesses m^3 formed in the lateral faces of the seat. 55 The lower face of this seat has a longitudinal groove m^4 in which the back of the horse enters at the end of the downward movement of the toy.

The seat m rests and slides at its rear end 60 upon two rollers m^5 rotatably mounted upon two spindles m^6 riveted to the upper ends of the two metal bars e^2 which are cranked for this purpose.

A spring n^1 fixed at one end to a hook n^2

screwed into the body of the horse h^2 and at 65 the other end to a bolt n^3 passing through the bars e^2 tends to draw together the lower parts of the two frames.

The steering rod b^2 (Figures 8 and 12) 70 fixed upon the axle b of the front truck presents in its upper face a recess q in the shape of a hollow spherical cap, in which there is fitted the bottom of a ball r screwed below the member d^1 of the front frame.

The members b^2 , r and d^1 are held in contact in this way by a bolt s passing through them, fixed rigidly at one end in the member d^1 by the nuts t and u and at the other end with a certain flexibility and a certain clearance in the steering rod b^2 so as to allow the 75 operation of the ball-joint r ; this is obtained by the wide aperture v and the spring w which presses on one hand upon the head of the bolt s and on the other hand upon the bar b^2 by means of the washers y and z .

The longitudinal members and the cross pieces are arranged in such a way that for 80 transport or when at rest, the two trucks can be folded right back.

The ratchet devices may act either upon 85 the wheels or upon the axles according to circumstances.

The various parts of the toy may represent 90 different subjects and receive decoration and ornamentation of any kind.

In general, the shapes and accessory arrangement of the various members of the devices described constituting materials and the details of construction may be varied 95 without departing from the present invention.

Having thus described my invention, what I claim is:—

1. A toy vehicle, comprising two frames, 100 a pivotal joint connecting said frames, trucks mounted at the lower ends of said frames, means for opposing backward movement of the vehicle, said means carried by said trucks, a seat rockably mounted upon one of said frames, rollers mounted upon the other of said frames, said seat resting at its rear end upon said rollers, and elastic connections between said frames said elastic connections tending to draw said trucks together in opposition to the rider's weight.

2. A toy vehicle, comprising two frames, 105 a pivotal joint connecting said frames, trucks mounted at the lower ends of said frames, means for opposing backward movement of the vehicle, said means carried by said trucks, a seat rockably mounted upon one of said frames, foot-rests upon the forward truck, and a ball-joint connection between said forward truck and the lower end of the frame upon which it is mounted.

In testimony whereof I hereunto affix my signature.

LOUIS FRANÇOIS AUGUSTIN FALKÉ.
